STOVE DOOR HINGE

Jesse W. Barker, Geneva, N. Y.

Original application February 24, 1933, Serial No. 658,421. Divided and this application September 2, 1933, Serial No. 683,053

1 Claim. (Cl. 126—194)

This invention is a divisional application of my co-pending application Serial No. 658,421 filed February 24, 1933, issued in Patent 1,969,197, August 7, 1934 and relates to improvements in stove door hinges and is especially intended for use on gas ranges for the oven and broiler compartments.

The invention has for its general object the provision of a stove door hinge of sturdy, yet light construction which can be quickly and conveniently assembled and disassembled.

A further object of the invention is to provide a stove door hinge having slip hinge connection which permits of a door being readily disconnected from the front frame of a stove.

A still further object of the invention is to provide a stove door hinge having a slip hinge connection which when used on a stove door will permit of the door spring being readily disconnected without the necessity of dismantling the door.

The detailed construction of the invention will be more particularly explained in connection with the accompanying drawings, wherein a preferred embodiment of the invention is illustrated.

25 In the drawings:

Figure 1 is a fragmentary vertical sectional view through a gas range showing the drop doors thereof in open and closed position and also showing in dash dotted lines a door pulled away from the frame;

Figures 2 and 3 are enlarged perspective views of the stove door hinge when disassembled. Thus Figure 2 is a perspective view of the pivot pin, seated in an apertured lug of the frame and Figure 3 is a perspective view of one of the hinge brackets arranged in a lower corner of a door;

Figure 4 is a fragmentary horizontal sectional view through the front frame of the oven showing the slip hinge connection between the door and front frame;

Figure 5 is a perspective view of the outer plate of the door with the truss rod in proper position; and

Figure 6 is a perspective view of the lining of the door with the slip hinge brackets attached thereto.

Referring more particularly to the drawings 1 denotes a gas range having a front frame or jamb 2 provided with the usual upper and lower baking oven and broiler compartment openings 3 and 4 respectively. The "drop doors" 5 and 6 for these compartments are hingedly connected to the frame at their lower ends in a manner hereinafter described, and as one door is sub-

stantially identical with the other, a description of the baking oven door 5 will suffice for both.

Door 5 comprises an outer or front pressed steel plate 7, the outer face of which is finished in enamel as usual, and an inner plate or lining 9 also of pressed steel construction. The outer plate 7 is formed on all four sides with a flange 10, extending at right angles to the face of the plate, the outer edge of this flange is rolled inwardly and downwardly upon itself to present a 10 smooth rolled edge portion 11, which greatly stiffens the plate and eliminates sharp edges which heretofore have frequently caused injury to workmen in the assembly and enamelling departments. These rolled edges at the lower side 15 of the front plate also cooperate with the slightly offset edge 12 of the lower side of the inner plate or lining 9 to facilitate assembly and to prevent separation of the two plates at this point. The top and two side portions of the plate 9 are 20 formed with slightly flexible right angularly extending flanges 15 which snugly engage the rolled edges 11 and rest against the inner face of the plate 7. The space between the two plates is 25 filled with heat insulating material 13, such as rock wool.

Angular hinge brackets or blocks 16, secured to the lower inner corner portions of the lining plate by screws 17 seat snugly against the side flanges 28 on plate 7. Apertured ears 18 formed 30 on the hinge brackets and extending through slots 19 in plate 9 and through slots 19' in the front frame of the stove are adapted to receive screws 20 to which the outer ends of the conventional counter balancing door springs 22 are 35 secured, but if desirable the springs may be hooked directly in the threaded openings 21. These springs extend horizontally to the rear of the oven between the outer side wall of the stove and the side lining, where they are connected to adjusting screws 25 extending through the back wall 26 of the stove. Removal of the springs for repair or renewal can be conveniently effected without dismantling the door, by merely taking down the lining plate 27 for the back wall of the 45 stove, and of course disconnecting the outer end of the springs from apertured ears 18. The latter operation can be accomplished without dismantling the door.

The upper sides or portions of the inner and 50 outer plates are securely fastened together adjacent their corners, the areas most likely to warp, by means of a tie or truss rod 29 which extends longitudinally of the doors and engages with its ends beneath the rolled edges 11 on the 55

side flanges 10. This bar rests upon the insulation 13 in spaced relation to the plates 7 and 9 and is secured to the inner plate 9 by headed screws 30 which pass loosely through openings 31 5 in the plate 9 and threadedly engage aligned threaded openings 32 in the tie rod. As the rod 29 does not directly contact with the inner faces of the opposing plates, it follows that when the screws 30 are screwed home the rod will be 10 silently drawn towards the lining plate into clamping engagement beneath the rolled edges 11. The slight bending of the tie rod gives the latter a truss effect and also prevents the screws 30 from becoming loose. Insulation 13 spaces 15 the bar a considerable distance from the inner face of plate 7 thus greatly facilitating proper alinement of the openings 31 and 32 preliminary to inserting screws 30. A handle member 33 is secured in place by means of a bolt, not shown, 20 extending through perforations 35 and 36 in the upper intermediate portions or sides of the respective plates 7 and 9. Side flanges 15 on the plate 9 are cut away at their upper corners as at 37 to permit clearance of bar 29. 25 Hinge brackets 16 are formed adjacent their lower corner edges with a central slot 38 for receiving apertured lugs 39 projecting forwardly from the front frame of the stove, and with side recesses or pockets 40 for pivotally seating pivot pins 41 extending loosely through the apertured lugs 39. When the door is closed the end walls 42 of the pockets will rest upon the pivot pins and pivotally support the door, and accidental displacement of the pins or disconnection of the 30 door from the frame will be prevented by the side walls 43 of the pockets. However it will be noted that when the door is swung to open or horizontal position, the door can be pulled away from the frame thus causing the pivot pins to 35 be withdrawn from the pockets. The door

springs 22, which resiliently maintain the slip hinge connection between the two parts of the hinge, of course must be disconnected before the door can be removed.

The lower side flange 10 of the front plate 7 5 is cut away at 44 adjacent its ends to expose the slotted and pocketed portion of the hinge brackets, and the latter extend very close to but terminate short of these openings to facilitate insertion of pivot pins 41 in their respective 10 pockets and to permit of close fit between the door and front frame.

Broiler door 6 is of substantially the same construction as door 5 with the exception that hinge brackets 16' are formed with a long arm 15 18' in lieu of the apertured ears 18. The slots 19" in the lining plates through which the arms 18' extend are also somewhat longer than the slots 19. Coil springs 22' connected at their upper ends to openings 20' in the arms 18' are 20 connected at their lower ends to the front frame 2. Shoulders 44' on bracket arms 18' engage the upper ends of slots 19' and support the door when in open position.

Having thus described my invention, what I 25 claim is:

An improved range door hinge, comprising a door frame, a door having a front panel and a slotted rear panel, hinge brackets between said panels secured to the inner face of said rear 30 panel and having an arm extending through the slot in said rear panel, each of said brackets having an exposed portion formed with a central slot and side pockets, apertured lugs on said door frame engaging in said central slots, pins loosely 35 mounted in said lugs and removably seated in said side pockets, and springs connected to said arms and to a fixed part of the stove.

JESSE W. BARKER. 40
